UNITED STATES PATENT OFFICE.

CHARLES H. ALLEN, OF PITTSBURGH, PENNSYLVANIA.

FLOATING TOOL-CHUCK.

1,322,474.

Specification of Letters Patent. Patented Nov. 18, 1919.

Application filed March 16, 1918. Serial No. 222,815.

To all whom it may concern:

Be it known that I, CHARLES H. ALLEN, a citizen of the United States, residing at Pittsburgh, in the county of Allegheny and State of Pennsylvania, have invented certain new and useful Improvements in Floating Tool-Chucks, of which the following is a specification.

This invention relates to improvements in drilling and boring apparatus and particularly to such type of devices adapted for drilling or boring polygonal holes.

The primary object of this invention is to provide a drilling or boring device of the type set forth for holding and operating a drill or cutting tool in such manner that the vibration of certain parts of the device will permit the cutting edge of the drill or tool to travel and operate in the path corresponding to the lines and angles of any polygonal figure.

Another important object of this invention is to provide a device of the character described which will operate the cutting tool eccentrically with respect to a piece of work.

Further objects of this invention are to provide a drilling or boring device of the type specified which is simple in its construction and arrangement, strong, durable and efficient in its use, readily set up for use, consists of comparatively few parts and inexpensive to manufacture.

To the accomplishment of these and such other objects as may hereinafter appear, the invention consists of the novel construction, combination and arrangement of parts herein specifically described and illustrated in the accompanying drawing, wherein is shown an embodiment of the invention.

40 In the drawing forming a portion of this specification and wherein like numerals of reference designate corresponding parts throughout the several views:

Figure 1 is a side elevation of a device 45 for drilling or boring polygonal-shaped openings in accordance with this invention, with a portion shown in cross section.

Fig. 2 is a bottom view of the shank member.

50 Fig. 3 is a plan view of the locking ring.

Fig. 4 is a cross sectional view on the line $x-x$, Fig. 3.

Fig. 5 is a top plan view of the drill member.

Fig. 6 is an end view of the driving element.

Fig. 7 is a side elevation of the driving element.

Fig. 8 is a perspective view of the guide member.

Fig. 9 is a cross sectional view of the cutting tool on line $y-y$, Fig. 1.

Referring more in detail to the drawing there is shown in Fig. 1 a device for drilling or boring polygonal-shaped openings 65 and comprising the shank member 1 flexibly connected to the drill member 2 by the interposed links 3.

The shank member 1 is formed integrally with the usual tapered shank 4 for chucking the drilling device in the machine, and the drill member 2 is provided with the chuck 5 for attaching the cutting drill or tool 6 to the drill member.

The lower portion of the shank member 75 1 comprises a circular disk 7 having a centrally disposed and integrally formed depending sleeve 8 which is provided with a rectangular recess 9, extending into the disk 7 for the purpose hereinafter described. 80 The upper portion of the drill member 2 also comprises a circular disk 10 which has an oppositely disposed sleeve 11 and recess 12 formed therewith, relative to the shank member 1.

Rotation is transmitted by the shank member 1 to the drill member 2 by means of the driving swivel 13, the heads 14 and 15 of which are adapted to engage in the rectangular recesses 9 and 12, respectively. 90 The driving swivel 13, as illustrated in Figs. 6 and 7, is so shaped and constructed as to permit universal movement of the shank member 1 and the drill member 2 with the exception of rotation, as the heads 14 and 15, of the swivel, at the point of contact 16 with the walls of the rectangular recesses 9 and 12, are rectangular in cross section.

The lower face of the shank member disk 7, and the upper face of the drill member disk 10 are provided with the spherical depressions 17, in which are adapted to seat the enlarged spherical ends 18 of the links 3. The spherical ends 18, of the links 3, are

mounted and locked in their seats by the locking rings 19, which are provided with the key-shaped openings 20, permitting the passage of the spherical ends 18, and communicating with smaller spherical openings 21 which register with the spherical depressions 17 to complete the seat for the link ends 18.

The locking rings 19 are secured to the 10 disks 7 and 10 by means of screws which pass through apertures 22 in the disks, and which have a threadable connection through the apertures 23, in the locking ring 19.

The shank member 1 and the drill member 2 are normally held in alinement and centered by the action of the spiral coil spring 24 which embraces and incloses the disk portions of the shank member and the drill member, and the associated interposed 15 parts.

The caps 25, secured to the disk portions of the shank and drill members by the screws 26, overlap the ends of the coil spring 24 and hold the same in secured position.

25 It will be readily apparent that with the shank 4, of the device, fixedly chucked in a machine, the connection of the drill member 2 with the shank member 1, by the links 3, will permit universal lateral movements to 30 the drill member 2 relative to the shank member 1, but no vertical movements, and that rotation may be efficiently imparted thereto, by the driving swivel 13, regardless of such lateral movements.

35 The drilling or cutting tool used in connection with the device herein described must necessarily be constructed for drilling polygonal holes, and the contours of the openings must be defined by employing a 40 guide member provided with a polygonal opening identical to that which it is desired to make. The drilling or cutting tool when operating upon a piece of work requires one less lip or flute than the number of walls 45 of the opening: For example, when drilling a triangular-shaped opening having three walls, but two lips or flutes are employed. The drilling member 6, illustrated in Figs. 1 and 9, has three lips or flutes 27 50 and is designed for drilling rectangular-shaped openings.

The lips or flutes 27 are cut to radially divide the periphery of the body of the drill member 6 equally, and deep enough to allow 55 the chips or cuttings to pass out freely. The end of the cutting tool 6 or drilling member has lips or flutes which conform with those provided on the periphery and forms the cutting edge of the tool. The flutes or lips 60 27 on the periphery of the cutting tool simply act as guides and follow the angularity of the polygonal shaped opening in the guide member 28, which is shown in Fig. 8 as rectangular-shaped.

65 The guide member 28, having a polygonal

shaped opening 29 consists of a flat plate and during the drilling operation the guide member is clamped to the work, which with the said guide member remains stationary and the cutting tool 6 operates through the 70 opening 29. During a boring operation the work with the guide member 28 revolves around the drilling device which in this instance is fixedly held in the boring machine.

The lateral shifting movements of the 75 drill member 2 relative to the shank member 1 as hereinbefore described, which forces the flutes 27 of the cutting tool 6 to follow the contour of the polygonal-shaped opening 29 in the guide member 28 is well understood 80 and does not require a more extended explanation.

85 From the foregoing description taken in connection with the accompanying drawings, the advantages of the construction and the method of operation will be readily apparent to those skilled in the art to which the invention appertains, and while describing the principle of operation of the invention together with the device which is 90 now considered to be the best embodiment thereof, it is to be understood that the device shown is merely illustrative and that various changes in the form, proportion and the minor details of construction may be resorted to without departing from the principle or sacrificing any of the advantages of the invention as defined in the appended claims.

95 What I claim as new and desire to secure 100 by Letters Patent is:

1. A drilling device comprising a shank member, a drill member, links flexibly connecting the said members together, means for driving the said drill member in unison 105 with the said shank member and allowing lateral independent movements of the said drill member, and a coil spring yieldably forcing the said members in alinement with each other.

110 2. A drilling device comprising a shank member, a drill member, a driving element connecting the said members together for movement together and allowing lateral movements of one of the said members, and 115 yieldable flexible means for connecting the said members together, said yieldable flexible means including a coil spring connected to both of said members.

120 3. A drilling device comprising a shank member, a drill member, means for driving the said drill member from the said shank member and allowing independent lateral movements of the said drill member, links having a detachable connection with both 125 of said members, and a coil spring arranged concentrically of the center of the said members and connected to both of said members.

130 4. A drilling device comprising a shank member, a drill member, links having spheri-

cal ends, means engaging the said ends and connected to the said members for allowing the said links to oscillate, a driving element held in engagement with both of said members by said means, and a coil spring connecting the said members together for the purpose set forth.

5. A drilling device comprising a shank member, a drill member, links having spherical ends, plates inclosing the spherical ends and connected to the said members, a flexible connection between the said members, and a coil spring connected to the said members for the purpose set forth.

15. 6. A drilling device comprising a member having spherical depressions and a shank extending therefrom, a second member constructed to support a drill and provided with spherical depressions, links each having spherical ends engaging said depressions, a ring connected to each of said members and constructed to hold the spherical ends of the said links in said depressions, a driving element arranged between the said members 20 and of a construction to prevent independent rotative movement of the said members but allowing lateral movements of one of said

members, and a coil spring arranged concentrically of the said rings and connected to the said members.

30

7. In a drilling device as described, a plate having spherical depressions, a ring having key-shaped openings communicating with beveled seats, a pair of members each having spherical depressions, and a link having 35 an enlarged spherical end adapted to pass the key-shaped opening and be arranged in said seat and depression in the said member.

8. In a drilling device as described, a pair 40 of members each having spherical depressions and each provided with a rectangular recess, links having spherical ends arranged in the said depressions, and a driving element curved in predetermined directions exteriorly and of a rectangular shape in cross section and seated in said recesses for the purpose set forth.

45

In testimony whereof I affix my signature in the presence of two witnesses.

CHARLES H. ALLEN.
